AEROSOL FOGGER

Harold D. Johnson, Emmetsburg, Iowa, assignor to Aero-Dyne Corporation, Emmetsburg, Iowa, a corporation of Iowa

Filed May 19, 1964, Ser. No. 80,057

Term of patent 14 years

(Cl. D62—2)

FIGURE 1 is a perspective view of an aerosol fogger embodying the new design.

FIG. 2 is a rear elevation of the fogger shown in FIG. 1.

FIG. 3 is a side elevation of the fogger shown in FIG. 1.

FIG. 4 is a typical section taken through the frame of the fogger along the line 4—4 in FIG. 3.

FIG. 5 is a perspective view of a modified form of the fogger shown in FIG. 1.

FIG. 6 is a top view of the fogger shown in FIG. 5.

FIG. 7 is a front elevation of the fogger shown in FIG. 5.

The characteristic feature of my design resides in the specific configuration of the handle portion in combination with the specific nozzle as shown.

I claim:

The ornamental design for an aerosol fogger, as shown and described.
